UNITED STATES PATENT OFFICE.

ALEXANDER MILLER, OF LEYTONSTONE, ENGLAND, ASSIGNOR OF ONE-HALF TO
SYDNEY ARTHUR BARTHOLOMEW, OF LONDON, ENGLAND.

PROPELLUTION OF BOATS AND OTHER VESSELS.

Application filed October 22, 1921. Serial No. 509,500.

To all whom it may concern:

Be it known that I, ALEXANDER MILLER, a subject of the King of Great Britain, residing at Leytonstone, Essex, England, have 5 invented new and useful Improvements in the Propulsion of Boats and Other Vessels, of which the following is a specification.

My invention relates to improvements in the method of propelling boats and other 10 vessels by means of the horizontal reciprocation of a paddle or blade carried by an arm or the like to which it is so pivoted or attached that it can move relatively thereto and be utilized as a rudder for steering the 15 vessel to which it is attached when so desired.

According to the invention the paddle or blade is pivoted to the outer end of a frame which is attached to the lower end of a tiller 20 post or the like, the said frame being so constructed that the said paddle or blade can fit within it and act as a rudder.

When the device is to be used as a propeller, the blade is released from the frame 25 and swung outwards, so that as the tiller post is oscillated the said blade is reciprocated with a sweeping motion. The extent to which the blade can pivot in the frame is limited by stops of any suitable construction. For example, I may for this purpose attach a forked fitting to the blade which engages a stop on the frame, the said stop being advantageously a screw which serves to secure the blade to the frame when housed 30 in the latter. The frame is furnished with means whereby the paddle or blade can be secured in position when housed within the frame.

To enable the invention to be fully understood, I will describe it by reference to 40 the accompanying drawing, in which:—

Figure 1 is a side view of a boat fitted with one form of combined propeller and rudder, constructed according to the invention, and showing the parts in position for propulsion purposes.

Figure 2 is a plan view of the combined propelling and steering device.

Figure 3 is a view similar to Figure 2, 50 showing the parts in the position for steering.

Figure 4 is a view showing a modification in which the propelling device is adapted to an ordinary rudder.

Figs. 5 and 6 are an elevation and a plan 55 respectively, of a device for limiting the swing of the propeller blade.

Referring first to the construction illustrated in Figures 1 to 3, *a* indicates the hull of the boat, *b* the tiller or steering arm, 60 which is hinged to the stern of the boat at *c* in the ordinary way. *d* indicates the frame which is attached to the lower end of the tiller post and *e* is the paddle or blade which is pivoted to the outer end of the said frame 65 *d*. The connection of the paddle *e* to the frame *d* is effected, in the construction illustrated, by means of the upper and lower pivot pins *f* which pass through holes in the outer end of the said frame, the upper pivot 70 *f* being provided with a handle *g* by means of which the lower pivot *f* can be lifted and the propeller or blade turned from the position in which it can function as a propeller, as indicated in Figures 1 and 2, into 75 the position shown in Figure 3 in which it is folded within the said frame, and in which it can be locked by the engagement of a pin *h* on the frame, with a hole *i* in the handle *g* provided for the purpose, the said 80 lifting movement enabling the handle *g* to clear the pin *h* when the paddle is thus turned within the frame *d*.

Means are provided whereby the swing of the paddle or blade *e* in the frame *d* can be 85 limited in either direction so that the oscillation of the said blade when functioning as a propeller shall give the most efficient results.

Figure 4 shows a construction which is 90 very similar to that illustrated in Figures 1 to 3, the difference being that the frame *d* is attached to an ordinary rudder *j* which is cut away at its lower part to receive the same frame. In other respects, the device is 95 the same as that hereinbefore described and functions in the same manner.

Figures 5 and 6 show means for limiting the swing of the paddle or blade *e*, such means comprising a stop-piece *k* having 100 shoulders *l*, *m* on its surface which contact with a shoulder *n* provided in the end of the lower part of the frame *d*.

I claim:

1. Means for the propulsion of boats and 105 other vessels of the kind hereinbefore referred to comprising an oscillating paddle, a vibratory frame attached to the lower end

- 2
- of a tiller post and to the outer end of which frame the paddle is pivoted for propulsive purposes and within which frame the paddle can be turned and fixed so that the 15
5 combined frame and blade can act as a rudder, and means comprising a handle, whereby said blade may be turned from the position of a propeller into the position of a rudder.
- 10 2. Means for the propulsion of boats and other vessels, as claimed in claim 1, comprising stops on the vibratory frame for limiting the angle of the said paddle relatively to the said frame when used for propulsive purposes, a handle by means of 15
which the propeller blade may be folded back into position as a rudder, and means for locking said blade in said position.
3. Means for the propulsion of boats and other vessels, as claimed in claim 1, in 20
which the blade is provided with a U-shaped handle, said handle having a recess, a pin on the frame formed to fit in said recess, said handle being adapted to be turned back so that the recess and pin will register 25 and hold the blade in position as a rudder.

ALEXANDER MILLER.
